BUILDING WALL CORNER JOINT

Earl E. Styles, Gaylord, Mich., assignor to The Otsego Log Cabin Company, Gaylord, Mich., a corporation of Michigan

Application June 28, 1950, Serial No. 170,798

12 Claims. (Cl. 20—4)

1

This invention relates to a building construction and, more particularly, to the construction of a cabin from members which simulate logs.

It is an object of this invention to produce a cabin construction utilizing siding which is fashioned to simulate logs, the construction being designed such that no nailheads are exposed on the exterior of the main walls of the cabin thereby eliminating the familiar rust streaks on cabins of this type and permitting the easy maintenance of the exterior surface of the cabin with its natural unmarred finish.

In the drawings:

Fig. 1 is a fragmentary perspective view of a corner of a cabin constructed in accordance with the present invention.

Fig. 2 is a horizontal sectional view through one form of corner construction.

Fig. 3 is a horizontal sectional view of another form of corner construction.

Fig. 4 is a horizontal sectional view of a return corner construction.

Fig. 5 is a horizontal sectional view at a window.

Fig. 6 is a horizontal sectional view at the union of two panels of an outside wall.

Referring to the drawings and particularly to Fig. 1, there is illustrated a corner construction for a cabin which generally comprises siding members 10, exterior upright corner pieces 12 and 14, and interior corner pieces 16 and 18. Siding members 10 and corner pieces 12 and 14 are milled to provide the exterior surface thereof with a rounded contour which simulates a log. These members, as well as the other superstructure of the cabin, are supported upon a suitable foundation generally indicated at 20.

Members 12 and 14 are mitered along one edge as at 22 such that, when these members are arranged with the mitered edges abutting, a substantially right angle corner is formed. The inner faces 24 of these members are substantially flat, and the edges 26 opposite edges 22 are milled perpendicular to the inner faces 24. The inner upright members 16 and 18 are generally of the same shape, each being provided with opposite flat faces 28 and 30 and squared end faces 32 and 34. Member 16 is dimensioned in width such as to extend from the interior corner formed by members 12 and 14 outwardly flush with the end face 26 of member 12. Member 18 is dimensioned such as to extend from the inner face 28 of member 14 outwardly to a point substantially flush with the end face 26 of member 16. Members 16 and 18 are rabbeted along the outer edges thereof as indicated at 36. The ends of siding members 10 are fashioned to provide a tenon 38 which interfits with the rabbeted portion 36 of members 16 and 18. Tenons 38 are preferably formed on the inner face of siding members 10 to provide a shoulder 40 which abuts against the end faces 26 of members 12 and 14 to provide a very solid corner construction.

2

One method of assembling the corner shown in Fig. 1 is illustrated in Fig. 2. In this embodiment the upright members 12, 14, 16 and 18 are pre-assembled and shipped to the site of construction 5 as a prefabricated corner assembly. The inner and outer upright members are secured together by nails 42. As is illustrated in Fig. 2, nails 42 may be driven through members 12 and 14 from the exterior thereof into members 16 and 18. With this form of construction the heads of nails 42 will be visible on the exterior face of the corner assembly, but after these upright members are secured together, the entire assembly is submerged in a vat containing a conventional liquid wood sealing composition which seals the grain and serves to preserve the wood. The wood sealer coats the entire corner assembly including the heads of nails 42, and the nailheads are therefore effectively protected from the elements. When the corner assembly illustrated in Fig. 2 is employed, the siding members 10 are arranged with the tenons 38 projecting into the rabbeted portion 36 on members 16 and 18. Members 10 are thereafter readily secured to the corner assembly by driving nails 44 through members 16 and 18 along the outer edges thereof so as to extend through tenons 38 and into members 12 and 14, respectively. Nails 44 are, of course, selected such as to extend into members 12 and 14 but not all the way through members 12 and 14.

In Fig. 3 there is illustrated another corner assembly in which the individual upright members are secured together at the site of construction. 35 In this form of corner construction the siding members 10 are first assembled at the building site with members 12 and 14 with the tenons 38 overlapping the inner faces 24 of members 12 and 14 and with the shoulder portion 40 abutting against the end faces 26 of members 12 and 14. Siding members 10 are then secured to members 12 and 14 by nails 46 driven through the tenons from the inner face thereof into members 12 and 14. After siding members 10 are secured in this manner to the corner pieces 45 12 and 14 the inner upright members 16 and 18 are secured to the outer upright members 12 and 14 by nails 48 which are driven through members 16 and 18 from the inner faces thereof into members 12 and 14. It will be noted that in 50 this form of corner construction no nailheads whatever are visible on the exterior of the corner assembly.

There is also illustrated in Fig. 3 the convenient manner in which an inner wall surface such as panels 50 may be attached to the inside of the corner assembly when it is desired to provide a finish on the interior of the cabin other than that provided by the siding member 10. It will be observed that the inner faces 28 of members 16 and 18 are spaced inwardly from the inner face 52 of the siding members 10. Wall panels 50 can be nailed to the inner faces of members

16 and 18 and the space between panels 50 and siding members 10 can be filled, if desired, with conventional insulating bats 54.

In Fig. 4 I have illustrated the manner in which a return corner may be constructed by utilizing the principle of this invention. In the corner construction illustrated in Fig. 4 the exterior upright members 56 and 58 are formed similarly to the members 12 and 14 except that the mitered edge is fashioned such as to provide a return corner when these members are secured together along their mitered edges. The inner upright members 60 and 62 are rabbeted as at 64 in a manner similar to the rabbeted portions 36 of members 16 and 18. In this form of corner the siding members 10 may be nailed directly to the inner face of members 56 and 58 or, as illustrated, the siding members 10 may be arranged one upon the other in abutting relation with members 56 and thereafter the members 60 and 62 may be arranged to overlie the inner face of members 56 and 58 and the tenons 38 so that the entire assembly may be secured together by nails 66 driven from the inner faces of members 60 and 62 through tenons 38 and into members 56 and 58. It will be readily appreciated, of course, that the form of corner illustrated in Fig. 4 can be constructed as a prefabricated assembly in the same manner as described with the corner construction illustrated in Fig. 2.

In Fig. 5 I have illustrated the principle of this invention in connection with the outer wall construction at a window of the cabin. In the arrangement illustrated the sash is indicated at 70, the window frame at 72 and the screen at 74. Frame member 72 may be of conventional design to accommodate sash 70 and screen 74. Adjacent each side of the window there is provided an exterior upright member 76 and an interior upright member 78 which are spaced apart slightly by means of a spacer strip 80. Upright 76 is similar to members 12 and 14 except that upright 76 is squared along edges 82 at each side thereof. Member 76 is secured to the window frame by nails 84 driven through frame member 72 and into the edge 82 of member 76. The siding member 10 is secured to outer member 78 by nails 86 driven through the tenons 38 from the inner side of the members 10 and into the upright 76. Spacer strip 80 is secured to upright 76 by similar nailing. The inner upright member 78 is secured in place by nails 88 which extend therethrough from the inner face thereof and nails 90 are driven into the edges of member 78 through frame member 72.

In Fig. 6 there is illustrated the manner in which the principle of this invention can be applied at the union of two panels of an outside wall. In this arrangement an outer upright member 76 is employed together with an inner upright member 92. The siding members 10 are first secured to the upright 76 by nails 94 driven through tenons 38 from the inner face of siding 10 and into member 76 and thereafter the inner upright member 92 is secured in place by nails 96 driven through upright 92 from the inner side thereof through tenons 38 and into upright 76.

It will thus be seen that I have provided a cabin construction which is not only economical but which is designed for convenient and rapid assembly and which, at the same time, eliminates the necessity of exposed nailheads on the exterior of the cabin which are very apt to rust and streak or mar the natural appearance of the log siding. The only nailheads on the main

walls of the cabin which are visible from the exterior are those nails which in one form of the invention are driven prior to subjecting the pre-fabricated assembly to the vat-sealing treatment. In that form of the invention (Fig. 2), these nailheads are, however, effectively protected against the weather. In the other form of the constructions illustrated, the nailing is done entirely from the inner faces of the upright members and no nailheads whatever are exposed.

The particular composition employed for sealing the wood by the vat sealing process prior to assembly at the side of construction forms no part of the present invention. Any conventional composition used for this purpose may be employed. Typical compositions of a suitable material are as follows:

Composition A

	Per cent
Coumarone (indene resin)	11.7
Chlorinated-diphenyl resin	20.0
Tall oil glycerine ester	66.3
Phynyl mercury oleate (active)	2.0
	100.0

Composition B

	Per cent
Linseed oil	83
Modified phenolic resin	15
Phenyl mercury oleate (active)	2
	100

Although the siding members 10 and the upright members, which are provided with a somewhat rounded contour, may be milled from planking to provide them with an exterior surface which simulates a log, it will be appreciated that these members may, if desired, be milled directly from half logs to provide an authentic rustic appearance. These members are referred to herein broadly as siding and upright members which terms are intended to include members milled from planking or directly from logs.

I claim:

1. In a building of wood construction, means for connecting two angularly related side walls of the building comprising inner and outer upright members secured together to form an upright corner assembly having two vertical angularly related end faces, two angularly related outer faces, and two angularly related inner faces, one of said members being rabbeted along the vertical end faces thereof, said rabbeted portion cooperating with the adjacent face of the other member to provide vertical grooves in said vertical end faces of said corner assembly, said grooves being disposed between the abutting faces of said inner and outer members a plurality of solid, horizontal members positioned edgewise one above the other and forming exterior siding for the building, said siding members having their ends projecting into and substantially filling said vertically extending grooves, said grooves each being sufficiently deep and said inner faces being sufficiently wide relative to the thickness of said corner assembly to provide ample clearance for driving fastening members into said ends of said siding members and said outer members from the inner faces of said inner upright members, and headed drive fastening members for securing said siding to said corner assembly, said fastening members being driven outwardly from the inner face of the siding members into the ends of said siding members within said

grooves and into at least one of said inner and outer members, said fastening members being of a length such as to terminate at the leading end thereof at a point spaced inwardly of the outer face of said outer upright members.

2. The combination set forth in claim 1 wherein in the ends of said siding members are fashioned as tenons fitting within said grooves, said tenons providing a shoulder portion adjacent the ends of said siding members, said shoulder portion abutting against the vertical end face of said corner assembly.

3. The combination set forth in claim 2 wherein in said shoulder portion abuts against the vertical end face of said outer upright member.

4. The combination set forth in claim 1 wherein in said headed fastening members comprise nails.

5. The combination set forth in claim 1 wherein the inner face of said inner member is provided with a substantially flat surface portion which is spaced inwardly of the inner face of said siding members.

6. In a building of wood construction, means forming an upright member the outer face of which forms a portion of the exterior surface of the building, said upright member having a vertical groove extending along a vertical end face thereof, said groove being disposed intermediate the inner and outer faces of said upright member, a plurality of solid horizontal members positioned one above the other and forming the exterior siding of the building, said horizontal members having their ends fashioned into tenons disposed within said groove, the inner face of said upright member and said tenons being sufficiently wide to provide ample clearance for nailing through said tenons from the inner face of said upright member, and means for securing said siding members to said upright member comprising nails driven into said upright member from the inner face thereof and extending into said tenons, said nails being shorter than the thickness of said upright member so that their ends do not penetrate through the outer face of said upright member.

7. The combination set forth in claim 1 wherein the inner face of said inner upright member is disposed inwardly of the inner face of said siding member, and including means forming an interior wall surface secured to the inner face of said upright member in spaced relation to the inner face of said siding members.

8. In a building of wood construction, means for connecting two angularly related side walls of the building comprising inner and outer upright members secured together to form an upright corner assembly having two vertically extending, angularly related end faces, two angularly related outer faces, and two angularly related inner faces, at least one of said members being rabbeted along the vertical end faces thereof, said rabbeted portion cooperating with the adjacent face of the other member to provide vertically extending grooves in said vertical end faces of said corner assembly, a plurality of horizontally extending siding members positioned edgewise one above the other and forming the exterior siding for the building, said siding members being defined on the one side by a continuous inner face and on the other side by a continuous outer face, said siding members having their ends projecting into and substantially filling said vertically extending grooves, said grooves having a depth less than the width of the angu-

larly related inner faces of said corner assembly and said angularly related inner faces of said corner assembly each having a width of sufficient dimension to provide ample clearance for driving fastening members through said inner upright member and into said outer upright member in a direction outwardly from said angularly related inner faces and substantially perpendicular to said angularly related inner faces, and headed drive fastening means for securing said siding members to said corner assembly, said fastening members being driven in a direction outwardly of said corner assembly through the portions of said siding members disposed within said grooves and into said outer upright member, said fastening members being of a length such as to terminate at the leading end thereof at a point spaced inwardly of the outer face of said upright members.

15 9. The combination set forth in claim 8 wherein in said grooves are dimensioned greater in depth than the width thereof.

10. The combination set forth in claim 9 wherein the ends of said siding members are fashioned as tenons fitting into said grooves, said tenons providing a shoulder adjacent the ends of said siding members which, when the tenons are disposed within said grooves, abut against the end face of at least one of said inner and outer

30 upright members.

11. A cabin construction including a corner assembly comprising inner and outer upright members secured together to form an upright corner post, said corner post having two vertically extending, angularly related inner faces and two vertically extending, angularly related end faces, at least one of said inner and outer members being rabbeted along the vertical end faces thereof, said rabbeted portion cooperating with the adjacent face of the other member to provide vertical grooves in said vertical end faces of said corner post, a plurality of planking members extending horizontally and positioned edgewise one above the other, the ends of said planking members projecting into and substantially filling said vertically extending grooves, said planking members forming the exterior surface of said cabin, said angularly related inner faces being sufficiently wide to provide ample clearance

50 for driving nails in a direction outwardly from said inner faces through said inner upright member and into said outer upright member, and means for securing said inner upright member, said outer upright member, and said planking members together comprising nails driven in a direction outwardly through the end portions of said planking members and through said inner upright member, said nails terminating at their leading ends inwardly of the outer faces of said outer upright member.

60 12. The combination set forth in claim 11 wherein the ends of said planking members are fashioned as tenons.

EARL E. STYLES.
